(57) CLAIM

I claim the ornamental design for a hooded garment, as shown and described.

DESCRIPTION

FIG. 1 is a front perspective view of the hooded garment for a right-handed person;

FIG. 2 is a front view thereof;

FIG. 3 is a back view thereof;

FIG. 4 is a right side thereof; and,

FIG. 5 is left side view thereof.

The stippling shown in the drawings represents a contrast of appearance.

The broken lines depict portions of the hooded garment that form no part of the claim.

The article shown in FIGS. 1 to 5 is made for wearing by a right-handed person. The applicant asserts design rights in the mirror images of all variants made for the left-handed person.
